UNITED STATES PATENT OFFICE.

ALBERT U. GRUMMANN, OF INDIANAPOLIS, INDIANA, ASSIGNOR OF ONE-HALF TO JOHN F. BROWN, OF SAME PLACE.

BARREL-SKID.

SPECIFICATION forming part of Letters Patent No. 311,655, dated February 3, 1885.

Application filed December 13, 1884. (No model.)

To all whom it may concern:

Be it known that I, ALBERT U. GRUMMANN, of the city of Indianapolis, county of Marion, and State of Indiana, have invented certain new and useful Improvements in Barrel-Skids, of which the following is a specification.

The object of my said invention is to provide an effective and convenient means whereby barrels may be rolled or piled up in tiers, one above another, without the strain and labor of lifting them bodily. This object is accomplished by constructing a skid provided with legs at one end, (which are commonly made adjustable, so as to reach two or more tiers,) and attaching thereto a pivoted supplemental skid adapted to be swung around, so as to extend out from the elevated end of the main skid in any direction. The apparatus also preferably includes a turn-table at the top of the main skid and means for automatically returning it to position.

Referring to the accompanying drawings, which are made a part hereof, and on which similar letters of reference indicate similar parts, Figure 1 is a perspective view of one of my improved skids as it appears when in use; Fig. 2, a top plan of the same; Fig. 3, a side elevation thereof; Fig. 4, an end elevation; Fig. 5, a side elevation with the adjustable legs extended; Fig. 6, an end elevation of the same; Fig. 7, a detail sectional view on the dotted line *z z* in Figs. 2, 4, and 8; and Fig. 8 a detail under side plan, looking upwardly from the dotted line *y y* in Fig. 7.

In said drawings the portions marked A represent the main skid, B the supplemental skid, and C the turn-table. The skid A has legs A' at one end, and preferably strengthening-braces A² extending from near the bottom of said legs to a suitable point on the body of the skid, as shown. The cross-bars connecting the sides of this main skid are preferably made of bar-iron, the ends thereof being bent at right angles and bolted fast to said sides. The upper one of these cross-bars is arranged to cross the space between the skid-sides on a level with their upper surfaces, while the others are preferably inverted and cross on a level with the lower surfaces of said sides. The upper one is thus adapted to form a bearing-plate, upon which the supplemental skid

and the turn-table are mounted and operate, and the position of the lower ones permits the supplemental skid to lie between the sides of the main skid when the device is not in use. Extension-legs A³ are mounted in clips a' on the legs A', and slide therein. When the skid is used to roll barrels up into a second tier, as shown in Fig. 1, these extension-legs are left out of use alongside the main legs A'. When a third tier is to be put in place, the skid is raised, these extension-legs run down and turned until the projections a³ thereon engage with the projections a² on the legs A', as shown in Figs. 5 and 6. There may be two or more of these projections a², in order to the better accommodate the device to use in piling up barrels of different sizes. Where the barrels are uniform in size, but one is needed. The supplemental skid B is mounted upon a pivot, b, extending through its end and through the upper cross-bar of the skid A, and is adapted to swing thereon, so as to extend out in any desired direction from that point. It is hinged at b', and its outer end thus adapted to be raised and lowered, as well as swung around from side to side. It is also preferably constructed in two sections, as shown, and is thus made adjustable, one of said sections being provided with clips, through which the ends of the other pass. The pivot b is revoluble and provided with an arm, b², to which a spring, a⁴, secured to the frame of the skid A is attached. The operation of this is to return the pivot to its ordinary position when the force thereon is released after it has been turned around to another position, for purposes which will presently be explained. The turn-table C is provided with a shank, c, preferably square, which is mounted in a corresponding hole or socket in the pivot b. The turn-table is thus adapted to be turned with said pivot in any direction, and to be returned to its normal position in line with the main skid A by the spring a⁴, upon being released, ready to serve as a stop for the barrels as they arrive at the top of the skid.

The operation is as follows: The skid being in position, as shown in Fig. 1, the barrels are rolled up the main skid A against and upon the turn-table C, and are stopped or prevented from rolling off over the end of the skid there-

by. When in position on the turn-table, the barrel, together with said turn-table, is whirled about, so that the side which faced down the main skid during the ascent shall face outwardly along the supplemental skid toward the place it is desired that the barrel shall occupy. The barrel is then rolled off the turn-table onto and along said supplemental skid to said place, the turn-table being meanwhile returned to position by the spring a' , ready to receive another barrel as it comes up the skid. The turn-table is capable of being removed altogether when desired, and thus when the supplemental skid is arranged in line with the main skid the barrels are permitted to be rolled directly from one to the other without stopping.

Having thus fully described my said invention, what I claim as new, and desire to secure 20 by Letters Patent, is—

1. The combination of the main skid A, elevated at one end, and the supplemental skid B, pivoted thereto upon the elevated end, substantially as set forth.
2. The combination of a main skid elevated at one end and an extensible supplemental skid, substantially as set forth.
3. The combination of the main skid A and the supplemental skid B, pivoted thereto and 30 constructed of sections adjustable upon each other, substantially as set forth.

4. The combination of the main skid, a supplemental skid, and the turn-table, substantially as set forth.

5. The combination of the main skid, the 35 supplemental skid, and the turn-table mounted in a revolable pivot having an arm by which said pivot and turn-table are automatically returned to position, substantially as set forth.

6. The combination, with a barrel-skid, of 40 a spring-mounted turn-table, the spring whereof operates to return the turn-table to its normal position.

7. The combination, with a barrel-skid provided with legs, of supplemental or adjustable 45 legs, whereby the height of the elevated end of the skid can be regulated, substantially as set forth.

8. The combination of the skid A, having legs A', on which are clips a' , and projections 50 a^2 of supplemental or extensible legs A ^{3} , mounted in said clips and having projections a^3 , substantially as set forth.

In witness whereof I have hereunto set my hand and seal at Indianapolis, Indiana, this 55 8th day of December, A. D. 1884.

ALBERT U. GRUMMANN. [L. S.]

In presence of—

C. BRADFORD,
CHAS. L. THURBER.
